Samuel H. Ransom, of Albany, N. Y.
Letters Patent, No. 772. Dated April 1, 1856.

The schedule referred to in these Letters Patent,
and making part of the same.

To whom it may concern:

Be it known that I Samuel H. Ransom of the City of Albany in the State of New York, have produced a new and original Ornamental Design for a Parlour Stove, and I hereby declare the annexed Drawings to be a full and accurate description and delineation of the ornamental parts with their several ornaments, the end plates not represented being symmetrically similar to the ones shown, and the halves of plates not shown being also symmetrically similar to those shown.

What I claim as my production and desire to secure by Letters Patent, is the combination and arrangement of ornamental figures and forms represented in the accompanying drawings forming together the ornamental Designs for the plates of a Parlour Stove. Albany March 10th 1856.
